The ornamental design for the cabinet, as shown and described.

DESCRIPTION

FIG. 1 is a perspective view of a cabinet in accordance with the new design;

FIG. 2 is a front elevational view thereof;

FIG. 3 is a top view thereof;

FIG. 4 is a right side elevational view thereof, the left side elevational view being a mirror image thereof;

FIG. 5 is a rear elevational view thereof;

FIG. 6 is a perspective view thereof illustrating the zipper in a partially opened position;

FIG. 7 is a perspective view of an alternative embodiment of the cabinet in accordance with the design illustrating the zipper in a partially opened position and the outer covering being a non-transparent material extending around the front, top, back, and left and right sides; and,

FIG. 8 is a perspective view of a second alternative embodiment of the cabinet in accordance with my new design illustrating one zipper in a partially opened position and the other zipper in a closed position.

The fragmented crisscross shading in FIGS. 1–6 and 8 is representative of a material which may be transparent or semi-transparent and which is understood to be continuous throughout the implied area. The broken lines are for illustrative purposes only and form no part of the claimed design.
